UNITED STATES PATENT OFFICE.

WILLIAM RAMSEY VAN BUSKIRK, OF PATERSON, AND JOHN ALLEN COOPER, OF JER-
SEY CITY, NEW JERSEY; ELMIRA VAN BUSKIRK ADMINISTRATRIX OF SAID VAN
BUSKIRK, DECEASED.

WATER-GAGE.

1,110,974.

Specification of Letters Patent. Patented Sept. 15, 1914.

Application filed May 10, 1912. Serial No. 696,429.

To all whom it may concern:

Be it known that we, WILLIAM RAMSEY VAN BUSKIRK, a citizen of the United States, and residing at Paterson, Passaic county, New Jersey, and JOHN ALLEN COOPER, a citizen of the United States, residing at Jersey City, in the county of Hudson and State of New Jersey, have invented new and useful Improvements in Water Gages, of which the following is a specification.

This invention relates to water gages and its object is to provide a substantial device not liable to breakage and damage as is so frequently the case in this class of articles, and consists of several cylinders of glass, the inner one forming a part of a water tube, the same being surrounded by an outer glass cylinder which is inclosed by a metal casing having longitudinal slots to exhibit the height of water in the gage.

These and other objects and details of the invention are more fully described in the following specification, set forth in the claims and illustrated in the drawings, wherein;

Figure 1 is a side elevation of the improved water gage. Fig. 2 is a vertical sectional view. Fig. 3 is a top plan view. Fig. 4 is a cross sectional view. Fig. 5 is a detail view of the gasket to be used in the gage.

The gage consists of a continuous tube for the passage of water embracing the interior glass tube 10 of ordinary thickness and inclosed within an outer tube or cylinder 11 of greater thickness and forming a substantial protector for the interior tube but of sufficient transparency for the observation of the height of water within the tube 10.

Both of the tubes are inclosed within a casing 12, whose upper ends are provided with a hexagonal head 13 and threaded at both ends to receive the heads 14 and 15 which make connection with the boiler above and below the water line. The heads 14 and 15 are screwed into the ends of the casing 12 and each of these beads has a recess 16 for the reception of the ends of the tube 10.

Interposed between the heads 14 and 15 and the cylinder 11, are washers or gaskets 17, which, when pressure is exerted

upon them by the heads, they are caused to expand and fill the joints between the heads and the tube 10 so as to make the latter thoroughly water-tight and prevent the escape of either water or steam. This gasket is made with outer flanges 18 and interior flanges 19, the flanges being adapted to fit in the openings which may exist between the adjacent parts. The casing 12 is provided on its several sides, with slots 20 so that the tube 10 and its contents may be observed.

This device forms a strong and substantial water gage, capable of resisting the rough usage which such devices are generally subjected to and where the metal casing is not sufficient to withstand the accidental blows, the cylinder 11 will afford abundant protection for the interior tube.

It is obvious that the parts may be otherwise arranged or modified without departing from the essential features above described.

The tube 10 is not only protected against injury from violence but it is relieved of sudden changes in temperature by the protecting cylinder which retains its heat and prevents its sudden cooling by rain or snow, or by cold weather and wind. If the inner tube should break its work would be performed by the outer cylinder and the leakage of water and steam prevented until the repairs are made, the outer cylinder thus performing the part of a gage in the usual way.

What we claim as new is:

A gasket adapted to be used in water gages comprising a disk having a peripheral flange at one side only and a central opening, said disk having flanges surrounding said opening and located respectively on the opposite sides, the last mentioned flanges being of the same diameter and being beveled at their outer edges.

In testimony whereof we affix our signatures in presence of two witnesses.

WILLIAM RAMSEY VAN BUSKIRK.
JOHN ALLEN COOPER.
